UNITED STATES PATENT OFFICE

128,795

DESIGN FOR LITHOGRAPHED SHEET METAL FOR METAL CONTAINERS OR THE LIKE

Everett E. Engstrom, White Plains, N. Y., assignor
to National Can Corporation, New York, N. Y.,
a corporation of Delaware

Application June 20, 1941, Serial No. 101,579

Term of patent 7 years

To all whom it may concern:

Be it known that I, Everett E. Engstrom, a citizen of the United States and a resident of White Plains, county of Westchester, and State of New York, have invented a new, original, and ornamental Design for Lithographed Sheet Metal for Metal Containers or the like, of which the following is a specification, reference being had to the accompanying drawing, forming a part thereof, wherein,

The figure is a plan view of lithographed sheet metal for metal containers or the like showing my new design.

I claim:

The ornamental design for lithographed sheet metal for metal containers or the like, substantially as shown.

EVERETT E. ENGSTROM.
